ATTORNEY

UNITED STATES PATENT OFFICE

GEORGE W. MILLER, OF SAPULPA, OKLAHOMA

CLEAN-OUT BIT FOR SAND PUMPS

Application filed April 2, 1930. Serial No. 441,047.

My invention relates to bailers and more particularly to a drill or bit attachment for use in combination with a bailer, the principal object of the invention being to provide a removable drill or bit element for readily replacing the bailer bottom ordinarily supplied.

It is a further object of my invention to include improved means for unloading from the bit element the débris and liquid collected in the bailer.

In accomplishing these and other objects of my invention I have provided improved details of structure the preferred form of which is illustrated in the accompanying drawing, wherein:

Fig. 1 is a vertical section of the lower end of a well hole partially cased, and in which is shown in elevation a bit element embodying my invention, attached to a bailer.

Fig. 2 is a detail perspective view of the bit element shown in disassembled relation with the lower end of the bailer body.

Fig. 3 is central section of the lower end of the bit element particularly illustrating the trap valve and unloading body.

Fig. 4 is a similar view in transverse section to that of Fig. 3, illustrating particularly the diverging channels and cutting edge of the bit.

Fig. 5 is a cross-section on the line 5—5, Fig. 3.

Referring more in detail to the drawing:

1 designates a well hole partially lined with casing 2, a bailer 3 being suspended in the well from a sand line 4.

The combination tool includes a tubular bailer member 5, and a bit attachment 6, adapted to be removably attached to the lower end of the bailer by a bayonet joint 7, and comprising the invention of my present application.

The bit element includes a head 8, a body portion 9 and a reduced neck 10 on its upper end provided with lugs 11 adapted to engage

slots 12 formed in the lower end of the tubular body member and terminating in lateral slots or sockets 13. The bayonet joint thus formed is held in locked position by a sliding plate 14 seated in dove-tailed grooves 15 of the body member and latched in open or closed position by a pin 16 engaging notches 17 or 18 selectively.

An interior channel 19 formed in the bit element, and communicating with the channel of the tubular body, terminates at its lower end in branch outlets 20 and 21 opening to opposite sides of the bit head and communicating respectively with tapered faces 22 and 23 converging in a cutting edge 24.

Cooperating with a valve seat 25, formed slightly above the branch outlets by an enlarged chamber 26 in the interior channel 19, is a flap valve 27, mounted on a pivot pin 28; a lateral discharge port 29 of the enlarged chamber being provided with a notch 30 for receiving the hinge bearing 31 of the valve.

The outer surface of the bit member surrounding the discharge port is flattened to form a plane face 32 to snugly contact with the flat inner face 33 of a closure door 34, hinged at its upper end by a bearing boss 35 seated in a socket 36 of the body portion and mounted on a pivot pin 37. A reinforcing rib 38 on the inner lower edge of the door is adapted to engage a cooperating tangential groove 39 of the body portion when the door is closed.

Various means may be provided for securely retaining the door in closed position but I have illustrated for this purpose a bolt 40, threaded into an opening 41 of the bit element adjacent the door opening, and including a head 42 having a tool slot 43; the bolt head, normally projecting over the lower edge of the door, being flattened as at 44 to permit opening and closing of the door.

To compensate for the thickness of the bolt head, the door and bit are recessed as indicated at 45 and 46 respectively, so that no

projections will extend beyond the outer surface of the bailer body to interfere with operation thereof.

When a bit element, constructed and assembled as described, is attached to a bailer and lowered into a well, liquid and débris is forced through the outlet branches against the flap valve, opening the valve and flowing into the continuous channel of the bit element and bailer. Hardened formation is broken up by the cutting edge of the bit as in ordinary cable drilling practice and is likewise forced through the open valve.

Upon upward movement of the bailer the flap valve immediately closes, trapping the charge within the tool. The bailer is then elevated to the top of the well and the charge is released therefrom by opening the door 34.

Because of the location of the trap valve near the bottom of the tool, a maximum amount of space is available within the tool for containing the débris as it is elevated from the well.

Due to the structure of the swinging door, the bailer may be readily relieved of its contents, and the necessity of removing the bit element from the bailer body to discharge contents therefrom is eliminated.

What I claim and desire to secure by Letters Patent is:

1. In combination with a barrel having a side opening, a flat face about the opening and a groove at one end of the opening, a valve for closing the barrel channel adjacent the bottom of the side opening, a door on the barrel adapted for closing the side opening and having a rib adapted to seat in said groove, and a latch on the barrel cooperative with the door to retain the door in closed position.

2. In combination with a barrel having a side opening and a groove at one end of the opening, a valve for closing the barrel channel below the side opening, a door pivotally mounted on the barrel adapted for closing the side opening and having a rib adapted to seat in said groove, and latching means cooperative with the door and barrel to retain the door in closed position.

3. In combination with a barrel having a side opening and a groove in transverse relation to said opening, a valve for closing the barrel channel below the side opening, a door pivotally mounted on the barrel adapted for closing the side opening and having a transverse rib adapted to seat in said groove, and a latch on the barrel cooperative with the door to retain the door in closed position.

4. In combination with a barrel having a side opening and a groove below the opening, a valve for closing the barrel channel below the side opening, a door hinged at its upper end to the barrel adapted for closing the side opening and having a rib adapted to seat in said groove, and latching means on the barrel

for retaining the door in closed position.

5. In combination with a round barrel having a side opening, a socket leading from the upper end of the opening and a flat face surrounding the opening, a valve for closing the barrel channel adjacent the bottom of the side opening, a door for said opening having a boss hingedly mounted in said socket, the inner surface of the door being flat to seat on the flat face surrounding said opening and the outer surface of the door being curved to conform to the curvature of the barrel when the door is closed, and latching means for retaining the door in closed position.

In testimony whereof I affix my signature.

GEORGE W. MILLER.
